AIR FLOW CONTROL IN AIR METHOD
CLEANERS

Daniel Benson Repleglo, Berkeley, Calif., assignor
to The Ohio Citizens Trust Company, Toledo,
Ohio, a corporation of Ohio, as trustee

Application August 8, 1936, Serial No. 95,011

11 Claims.

(Cl. 15—9)

The invention relates to cleaning apparatus and more particularly to portable electric cleaners of the air method type, which may be selectively employed for floor cleaning purposes or by the use of suitable extension devices may be employed for cleaning walls, draperies or the like. Devices of this general character are known to the art and it is the object of the present invention to provide novel, simple and inexpensive means for at times connecting a floor tool of the cleaning apparatus with a source of suction and simultaneously cutting off communication between the source of suction and extension devices or the like, or for cutting off communication between the floor tool and the suction producing means and simultaneously placing the extension tool, or the like, in communication with the suction producing means.

According to the present invention the above object is attained by the use of a removable branched tubular fitting having a plurality of openings, preferably three, one of which is placed in communication with the source of suction while the other two are adapted to be placed in communication with the floor tool and with extension devices, one of the other of the latter openings being closed by a stopper while the other is unobstructed.

The invention will be more readily understood by reference to the accompanying illustrative drawing and the following detailed description.

In the drawing,

Fig. 1 is a side elevation of the assembled cleaner shown in floor cleaning position, portions being broken away to show the interior;

Fig. 2 is a fragmentary view showing the upper portion of the cleaner with extension cleaning members applied thereto; and

Fig. 3 is a detailed view of the branched tubular fitting.

Fig. 4 is a detailed view showing a spring holding means for retaining the fitting and cap in place upon the cleaner.

Referring to the drawing in detail, the reference numeral 10 denotes the cylindrical body portion of a cleaner of the general type illustrated in my Patent No. 1,887,600, dated November 15, 1932. In the lower part of the body is located a power plant 11 which may be similar to that referred to in my application Serial Number 56,384, filed December 27, 1935, now Patent No. 2,146,763, dated February 14, 1939, the power plant having a lateral discharge outlet or outlets 12 in a removable cap 13, as more fully described in the aforesaid application.

At the upper end of the body 10 is a removable cap 14 which fits within the cylindrical body. To the lower end of the cap 14 is detachably secured an air filtering and dust collecting bag 15, preferably composed of porous paper. This bag may be withdrawn from the tank or cylinder 10 when the cap 14 is removed. Preferably an outer coarse mesh reinforcing member 15a is likewise employed which may be composed of cloth, wire or the like, the outer element being separately removable, if desired, or it may be so arranged to be withdrawn with the inner bag and the cap 14.

At the top of the cap is a cover 16 which may be of glass or other transparent material and is provided with a centrally arranged opening 17 into which dust laden air is to be drawn from either of two sources through a removable branched tubular fitting A, which is one of the distinguishing features of the present invention and which is shown removed from the rest of the apparatus in Fig. 3.

The T shaped joint, fitting or coupling A is preferably composed of hard fibre tubing, or may be made of molded "Bakelite" or like material, or even of light metal such as aluminum. One leg 18 of the fitting is permanently secured to the top 16 of the transparent dust cap while the main portion 19 of the fitting is curved and serves as a handle grip by means of which the apparatus may be moved to and fro across the floor during the floor cleaning operation, and also as a handle for withdrawing the cap 14 and the inner dust collecting bag 15 from the cylindrical tank or caddy 10. The handle grip portion has an opening 20 at the end farthest from the transparent cap and tubular extension devices may be attached thereto. As shown in Fig. 2, a collar 21, which may be of rubber, fibre, "Bakelite," or other suitable material, connects a flexible hose 22 to the handle. The handle is shown as provided with a tubular nozzle 23 to which other extension devices may be attached if desired, as disclosed in my Patent No. 1,533,271, dated April 14, 1925.

Extending laterally from the main portion of the fitting intermediate the leg 18 and the handle 19 is a branch 24 which is provided with a downwardly extending portion 25 adapted to be placed in communication with a pipe 26 through a coupler 27 which coupler is preferably a part of a fitting which connects the pipe 26 to the body part 10. Either the extension 25 or the opening 20 in the end of the handle grip portion 19 is adapted to be closed by a stopper B while the other opening remains unobstructed. The stop-

55

per may be also used to close one of the two exhausts 12, the hose 22 attaching to the other for blowing purposes.

The pipe 26 is preferably of hard fiber, "Bakelite," or the like, and together with the fitting A may be regarded as constituting the handle of the cleaner. At its lower end the pipe 26 is removably fitted into a connector 28 shown as an extension of the cap 13 which closes the lower end of the body member 10. In this manner the pipe 26 and the body 10 may be held in fixed, parallel, spaced relation to each other. A short length of pipe 29, which may also be of hard fibre, "Bakelite," or the like, may be removably fitted 15 into the lower end of the coupler 28, thus being placed in communication with the pipe 26 at one end, while to the lower end a floor tool 30 such as is disclosed, for example, in my Patent No. 1,994,868, dated March 19, 1935, may be detachably secured, an inclined rotatable joint 31 being preferably included as described in the aforesaid patent, to permit the tool to rest upon the floor in spite of all angular variations of the remainder 20 of the apparatus.

25 Any suitable means may be employed for holding the fitting A and the cap 14 in place. As shown, a U shaped spring member 32 fits over the branch 24 of the fitting, and is provided with inwardly projecting prongs 33 which pivot to a portion 34 of the coupler 21. The holding member may be disengaged by swinging upwardly without releasing the prongs, whereupon the fitting A, the cap 14 and the paper dust collector 15 may be withdrawn by means of the handle portion 19.

40 A collapsible, hinged, wheeled bracket C may be employed for supporting the apparatus in floor cleaning position, as illustrated in Fig. 1, or may be folded downwardly against the body 45 of the cleaner when extension members are to be applied to the upper end of the suction handle for cleaning walls, etc. The details of the construction of the bracket per se are set forth and claimed in my co-pending application, Serial No. 94,653, filed August 6, 1936, entitled "Air-method cleaner supports."

50 The operation of the cleaner will now be briefly described. Assuming that the apparatus is to be employed for floor cleaning purposes as illustrated in Fig. 1, the bracket C will be opened and the cleaner may rest upon the floor tool and the supporting roller or rollers of the bracket. The opening 20 at the upper end of the handle grip 19 will be closed by the stopper B to prevent 55 air from being drawn thereinto. The electric motor with which the suction producing means 11 is equipped is now turned on and dust laden air will be drawn into the floor tool 30 and will pass through pipes 29 and 26 into the branched coupling A and thus through the transparent cover 16 into the dust collector and air filtering means 15 and 15a. The amount of dust being drawn into the apparatus may be viewed 60 through the transparent cap. The dust is separated from the air by the dust filtering means and is eventually discharged at 12.

65 When the apparatus is to be used in repose for other than floor cleaning purposes, the bracket C will be folded against the body of the cleaner so as to be out of the way. The fitting A with the bag connections may partly be removed from the cleaner and the stopper B taken out of the opening 20 in the handle grip 19 and placed in the opening at the lower end of the leg 25, after which the entire fitting is replaced,

as indicated in Fig. 2, and suitable extension cleaning members 21, 22 and 23 applied to the open end of the handle. Dust laden air may then be drawn into the cleaner through the nozzle 23, or other cleaning tool with which the apparatus is equipped. If desired the cleaner may be supported in upright position for repose operation by any suitable means such as shown, for example, in my Patents 1,884,864; 1,884,865; 1,884,866; 1,884,867; 1,884,868; 1,884,870; 1,970,- 10 576 and 1,983,567.

15 The invention has been described in detail for the purpose of illustration. It will be understood that variations and modifications may be resorted to without departing from the spirit of my invention.

I claim:

1. In a portable suction cleaner, including a cleaner body having a source of suction, and a tubular unit communicating with said source of suction and having two intercommunicating branches adapted to connect with cleaning tools at either end, said unit being slidably removable from the cleaner body, and means comprising a removable plug adapted to close either of said branches, whereby cleaning tools connected with the other of said branches will be placed in communication with the source of suction, one branch of said tubular unit comprising a handle grip for manually moving the cleaner across the floor. 25

2. A tubular T joint fitting in combination with an air-method cleaner, having a stopper fittable to either of two ends and a third end secured to a cap on the dust collector body of the cleaner and communicating with the interior thereof, 35 said fitting being adapted to be withdrawn lengthwise as a unit.

3. In a suction cleaner, a housing containing air filtering means communicating with a source of suction, a suction pipe rigidly secured at one side of said housing and communicating at one end with a cleaner tool, and a detachable tubular unitary fitting including a pair of freely communicating legs one of which is adapted to slidably connect with the free end of the suction pipe, and the other of which is provided with a cap slidably fitting said housing, said fitting being adapted to be withdrawn lengthwise as a unit, thereby allowing access to the interior of the housing, the fitting being provided with a 50 suction handle adapted to be connected to a suitable cleaning tool. 45

4. In a suction cleaner of the character described, a pair of tubular elements arranged side by side, one of said tubular elements containing 55 air filtering means communicating with a source of suction, and the other being adapted to connect to a cleaning tool at one end, and a detachable fitting including three rigidly connected freely intercommunicating tubular branches, one of which includes a cap for the filtering means, another being adapted to slidably connect with the end of the other tubular element, while the third branch comprises a tubular suction handle adapted to be connected with suitable cleaning tools; said fitting being slidably removable lengthwise as a unit; and means for controlling suction through said fitting. 60

5. In a portable suction cleaner, a housing containing air filtering means at one end communicating with a source of suction, a removable cap slidably fitting the air filtering end of said housing, a tubular element arranged at one side of said housing, with one end adjacent the filtering end of said housing, the other end being con- 75

- nectible to a cleaning tool, and a detachable fitting having three intercommunicating branches, one of which is secured to said removable cap, a stopper fittable to the open end of either of 5 the other branches, one of which is slidably connectible to the free end of the tubular element.
6. In a suction cleaner, a pair of tubular elements arranged side by side, a cap slidably fitting one of said tubular elements, a source of 10 suction, an open ended suction handle secured to said cap and communicating with the interior thereof, and a branch pipe extending laterally from said suction handle, and having an open end slidably fitting the other of said tubular elements, and means for controlling the suction 15 in the handle and the lateral branch, said suction handle, cap, and branch pipe being adapted to be withdrawn axially as a unit from said tubular elements.
7. In a suction cleaner, a pair of tubular elements arranged side by side, a cap slidably fitting one of said tubular elements, an open ended 20 suction handle extending from said cap and secured thereto, a branch pipe extending laterally from said suction handle, and having an open end slidably fitting the other of said tubular elements, said suction handle, cap, and branch pipe being adapted to be withdrawn axially as a unit from said tubular elements, and a stopper 25 adapted to be fitted into the open end of either the branch pipe or the suction handle for cutting off communication with said cap.
8. In a suction cleaner, a pair of tubular elements arranged side by side, one of said elements including air filtering means at one end 30 communicating with a source of suction and a cap at the air filtering end thereof, a unitary branched fitting comprising a curved open ended suction handle for manipulating the cleaner 35 projecting from said cap and a branch pipe extending laterally from said suction handle and adapted to slidably fit the other of said tubular elements, and means for controlling suction 40 through said fitting.
9. In a portable suction cleaner, a housing containing air filtering means at one end communicating with a source of suction, a removable 45
- able cap slidably fitting the air filtering end of said housing, a tubular element arranged at one side of said housing with one end adjacent the filtering end of said housing, the other end being connectible to a cleaning tool, a suction handle secured at one end to said cap and the other end being connectible to extension elements, and a branch pipe extending laterally from the suction handle, intermediate its ends with its free end slidably fitting the top of said tubular element, said suction handle, cap and branch pipe being adapted to be slidably withdrawn as a unit from said housing and tubular element, and means for controlling the direction 10 of fluid flow in the branch pipe and suction 15 handle.
10. In a portable suction cleaner, a pair of tubular elements arranged side by side and rigidly connected, one of said elements including suction producing means, and a branched 20 tubular fitting serving to connect adjacent ends of said tubular elements, and having two branches adapted to communicate with each of said tubular elements and a third branch adapted to serve as a suction handle adapted 25 to be connected to a suitable cleaning tool, said fitting being slidably removable lengthwise as a unit from said tubular elements, and means for controlling the direction of fluid flow through 30 said fitting.
11. In combination with a dust collector comprising a cylindrical housing containing air filtering means communicating with a source of suction, a removable cap for said housing, a tubular element secured parallel to the cylindrical housing with one end communicating with a suitable cleaning tool, and the free end adjacent said air filtering means, and a fitting 35 having three tubular branches, one being secured to said cap, another being slidably connectible to the free end of said tubular element, and a third comprising a suction handle, and a stopper fittable to the open end of either of 40 said last named branches for at will cutting off communication with the branch which is secured 45 to said removable cap.

DANIEL BENSON REPLOGLE.
